UNITED STATES PATENT OFFICE.

CLARENCE P. CHAMBERLIN, OF DETROIT, MICHIGAN, ASSIGNOR TO JOSEPH N. SMITH & COMPANY, OF DETROIT, MICHIGAN, A CORPORATION OF MICHIGAN.

SASH-OPERATING MECHANISM.

Application filed November 9, 1921. Serial No. 512,585.

To all whom it may concern:

Be it known that I, CLARENCE P. CHAMBERLIN, a citizen of the United States, residing at Detroit, county of Wayne, State of Michigan, have invented a certain new and useful Improvement in Sash-Operating Mechanism, and declare the following to be a full, clear, and exact description of the same, such as will enable others skilled in the art to which it pertains to make and use the same, reference being had to the accompanying drawings, which form a part of this specification.

This invention relates to sash operating mechanisms and the object of the invention is to provide a sash operating mechanism for use with closed vehicle bodies and the like which is very efficient in operation and which will not easily get out of order. Another object of the invention is to provide a sash operating mechanism in which the sash may be raised or lowered by applying a slight pressure by hand in turning the crank. A further object of the invention is to provide a sash operating mechanism in which the sash is securely supported in position at any point within its path of travel during rotation of the crank and upon cessation of rotation thereof. A further object of the invention is to provide a sash operating mechanism comprising a vertical rack, a gear meshing therewith supported on and movable longitudinally of a vertical screw shaft, the said gear being provided with an arm connected to the sash whereby rotation of the gear moves the sash up or down in the frame therefor. Another object of the invention is to provide a sash operating mechanism in which the weight of the sash is counterbalanced so that the sash may be raised as easily as lowered. These objects and the several novel features of the invention are hereinafter more fully described and claimed and the preferred form of construction by which these objects are obtained is shown in the accompanying drawings in which—

Fig. 1 is a side elevation of the door of a closed body vehicle provided with my improved sash operating mechanism.

Fig. 2 is an enlarged section taken on line 2—2 of Fig. 1.

Fig. 3 is a section taken on line 3—3 of Fig. 1.

Fig. 4 is a sectional detail of the support 55 for the lower end of the vertical screw shaft.

As shown in Fig. 1 a door frame 1 is provided having a frame part 2 extending thereacross. The sash 3 for the window glass 4 may be raised or lowered in the frame, the frame being provided with ways therefor. The lower edge of the sash 3 is provided with a way 5, shown more particularly in Fig. 2, in which a roller 6 engages which is rotatably mounted on the upper end of an arm 7. The arm 7 is formed integrally with or attached to a gear 8 which is rotatably mounted on a nut 9 provided with a member 10 preventing the gear from coming off from the nut. The nut 9 is threaded onto a vertical screw shaft 11 which has a bearing in the member 12 at the upper end which is supported on the plate 17, the upper end of the shaft 11 being provided with a beveled gear 13 secured thereto which meshes with a beveled gear 14 secured to a shaft 15. A bearing 16 is formed integrally with the plate 17 and is adapted to receive the shaft 15, the plate 17 being secured by the screws 18 to the frame member 2 which is shown more particularly in Fig. 1. The shaft 15 is provided with a collar 20 and the shaft is prevented from longitudinal movement in the bearing 16 by the bevel gear 14 at one end and by the collar 20 at the opposite end. The shaft 15 is provided with an extending threaded end 21 to which is secured the handle 22. It can thus be seen that upon rotation of the handle 22 the shaft 15 is rotated which rotates the beveled gear 14 thus rotating the beveled gear 13 and shaft 11 to which it is secured. The nut 9 is held from rotation by the engagement of the gear 8 between the two sides 23 of the toothed rack 24 and thus as the screw shaft 11 is rotated the nut 9 is moved up or down thereby. As shown in Fig. 1 the gear 8 is provided with teeth 25 which mesh with the teeth 26 on the rack 24 and as the nut 9 travels upwardly or downwardly on the screw shaft 11, the gear 8, due to its engagement with the rack 24, is rotated which moves the arm 7 through the arc of a circle as indicated by the position shown by dotted lines in Fig. 1. This movement of the arm due to its connection with the sash 3 moves the sash downwardly, the sash being supported at any point within

100
105

its path of movement by the engagement of the gear 8 with the toothed rack 24. The toothed rack 24 is supported in a bracket 27 at the lower end which is secured to a frame member 28 extending across and connected at each end to the frame members 1. This bracket 27 also supports the lower end of the screw shaft 11, as shown more particularly in Fig. 4. The lower end of the screw shaft 11 is recessed to receive a ball 29 which is supported in a plate 30 mounted within a chamber 31 and supported on a coiled spring 32, a plug 33 supporting the said coiled spring. It can thus be seen that due to its weight, the window glass 4, when the vehicle is traveling over a bumpy road tends to jar up and down in the frame which forcing down on the end of the arm 7 when in the dotted position shown in Fig. 1, causes the gear to oscillate which moves the nut 9 thus moving the shaft 11, the spring 32 taking up the movement and flexibly supporting the sash. It will be noted from Fig. 2 that the moving parts of the device are contained within the inner side board and the outer side board 34 of the frame, the rack 24 being secured to the outer side board by the screws 35 which extend through the rack 24 and through spacer blocks indicated by dotted lines 36 which space the rack on the member 34 to support it in alignment with the gear 8 shown in Fig. 2. The plate 17 is secured to the frame member 2 by the screws 18, the said plate 17 supporting the upper end of the screw shaft and rotating mechanism therefor, as hereinbefore described. As shown in Fig. 2, a rubber strip 38 is provided about the lower edge of the glass 4 and is held in place by the channel shaped metal sash 3. The frame member 34 is provided with a metal strip 39 which extends across the door and is secured to the member 34, the inwardly extending edge of the member 39 engaging the rubber strip 38 when the window is moved to the uppermost position, thus preventing water from entering between the glass 4 and frame member 34 which might damage the mechanism. As will be seen from Figs. 1 and 2, a spiral spring 41 is connected at one end at 42 to the nut 9 and the opposite end extends through and is secured to the gear 8 at 43. This spring acts as a counter-balance for the weight of the sash, the gear 8 being turned downwardly against the tension of the spring when lower the sash and when the gear 8 is again turned upwardly the spring 41 tends to turn the same upwardly so that the weight of the sash is not necessarily overcome by rotation of the handle, the rotation of the handle merely actuating the mechanism from which all strain has been thus relieved.

In operation the device is first considered to be in the uppermost position shown

in full lines in Fig. 1. Upon rotation of the handle 22 which is transmitted to the screw shaft 11, the nut 9 is moved downwardly on the said shaft which brings the center of the gear 8 down and due to its engagement with the rack 24 causes the said gear to rotate on the nut 9 against the tension of the spring 41 thus moving the gear to the dotted position shown in Fig. 1, which by means of the engagement of the roller 6 of the arm 7 in the way 5 of the sash 3 moves the sash 3 downwardly. It will be noted that by this construction the vertical movement of the sash is much greater than the vertical movement of the gear 8, the rotation of the gear causing a greater proportionate movement of the sash. The sash may travel to the lower cross piece 40 of the door the cross bar 28 being out of the path of movement of the said sash. When it is desired to again raise the window the handle 22 may be turned in the opposite direction which rotates the screw shaft 11 to draw the nut 9 upwardly which, with the assistance of the spring 41, turns the gear 8 back to the upper position shown in Fig. 1, thus raising the sash to the closed position.

From the foregoing description it becomes evident that the device is very simple and efficient in operation, providing a device whereby a sash may be easily and effectively raised or lowered by rotation of a crank and supported at any point within its path of travel and further provides a device which accomplishes the objects described.

Having thus fully described my invention, its utility and mode of operation, what I claim and desire to secure by Letters Patent of the United States is—

1. In a sash operating mechanism, a framework, a sash mounted to slide therein in a vertical plane, a rotatably mounted screw shaft, a non-rotatable nut in threaded relation therewith, a gear rotatably mounted on the nut, an arm extending from the gear and provided with a roller on the outer end thereof, a way on the sash in which the said roller is adapted to ride, a stationary rack in which the said gear meshes, and means for rotating the screw shaft.

2. In a sash operating mechanism, a framework, a sash slidably mounted therein, a vertical screw shaft rotatably mounted in the frame work, a nut adapted upon rotation of the screw shaft to travel longitudinally thereof, a gear rotatably mounted on the nut, an arm extending therefrom and connected with the sash whereby rotation of the arm and gear correspondingly raises or lowers the sash, a stationary rack in which the said gear meshes, and means for rotating the screw shaft.

3. In a sash operating mechanism, a framework, a sash mounted to slide therein

- in a vertical plane, a bracket extending across the framework, a screw shaft rotatably mounted therein, a non-rotatable nut in threaded relation therewith, a stationary 5 rack, a gear rotatably mounted on the nut and meshing with the said rack, an arm extending from the said gear and provided with a roller on the outer end thereof, a way formed in the lower sash bar in which the 10 said roller is adapted to ride, and means for rotating the screw shaft.
4. In a sash operating mechanism, a framework, a sash mounted to slide therein in a vertical plane, a bracket extending 15 across the framework, a vertical screw shaft rotatably mounted therein, a spring supporting the screw shaft, a non-rotatable nut in threaded relation with the said shaft, a rack mounted on the said bracket, a gear 20 rotatably mounted on the said nut and meshing with the said rack, an arm extending from the gear and provided with a roller on the outer end thereof, a way in the lower sash bar in which the said roller is 25 adapted to ride, and means for rotating the screw shaft.
5. In a sash operating mechanism, comprising in combination a framework having an opening in the upper part and the lower 30 part being formed with spaced walls, a sash slidably mounted in the frame adapted to be raised into the opening or to be lowered between the said walls, an operating mechanism for the sash consisting of a vertical screw shaft rotatably mounted in the framework, a non-rotatable nut in threaded 35 relation therewith, a vertical rack extending between the walls of the said framework, a gear rotatably mounted on the nut and meshing with the said rack, an arm extending 40 from the gear, a way in the lower sash bar in which the end of the said arm is adapted to ride and a crank for rotating the screw shaft.
- 45 6. In a sash operating mechanism, comprising in combination a framework having an opening in the upper part and the lower part being formed with spaced walls, a sash slidably mounted in the frame adapt-
- ed to be raised into the opening or to be lowered between the said walls, an operating mechanism for the sash consisting of a crank member on the inner wall of the frame and provided with a shaft extending therethrough, a gear mounted on the crank 55 shaft between the said walls, a second gear meshing therewith, a rotatable screw shaft to which the said second gear is secure, a non-rotatable nut in threaded relation therewith, a gear rotatably mounted on the nut, 60 an arm extending from the said gear and provided with a roller on the outer end thereof, a way on the sash in which the said roller is adapted to ride, and a stationary 65 rack in which the said gear meshes.
7. In a sash operating mechanism, a framework, a sash slidably mounted therein, a vertical screw shaft rotatably mounted in the framework, a nut adapted upon rotation of the screw shaft to travel longitudinally thereof, a gear rotatably mounted on the nut, an arm extending therefrom and connected with the sash whereby rotation of the arm and gear correspondingly raises or lowers the sash, a spring adapted 70 to counter-balance the weight of the sash, a stationary rack in which the said gear meshes, and means for rotating the screw shaft.
8. In a sash operating mechanism, a framework, a sash slidably mounted therein, a vertical screw shaft rotatably mounted in the framework, a nut adapted upon rotation of the screw shaft to travel longitudinally thereof, a gear rotatably mounted 75 on the nut, an arm extending therefrom and connected with the sash whereby rotation of the arm and gear correspondingly raises or lowers the sash, a stationary rack in which the said gear meshes, a spring 80 yieldably resisting rotation of the gear to lower the sash and assisting rotation of the gear to raise the sash, and means for rotating the screw shaft.

In testimony whereof, I sign this specification.

CLARENCE P. CHAMBERLIN.
